UNITED STATES PATENT OFFICE.

JOSEPH N. SUPRUNOWSKI, OF TOLEDO, OHIO, ASSIGNOR OF ONE-HALF TO JOEL DE VAULT, OF TOLEDO, OHIO.

CAR ATTACHMENT.

1,129,755.

Specification of Letters Patent. Patented Feb. 23, 1915.

Application filed July 22, 1914. Serial No. 852,500.

To all whom it may concern:

Be it known that I, JOSEPH N. SUPRUNOWSKI, a citizen of the United States, residing at Toledo, in the county of Lucas 5 and State of Ohio, have invented new and useful Improvements in Car Attachments, of which the following is a specification.

This invention relates to improvements in the air line equipment of cars.

10 The leading feature of my invention consists in providing a means combining the cut-off valve feature and dust collecting feature which concerns the air line mechanism with which railway cars are equipped. 15 The general practice in vogue today is such that two separate connections are necessary in the air line of a car for the distinct purposes of cutting off the flow of air from the air pump engine, and for collecting the 20 dust that may accompany the air through the various air pipes with which the car is provided.

One of the important objects of my invention consists in providing a simple, inexpensive, and highly efficient combined cut-off valve and dust collector for air line systems of cars which is characterized by simplicity of construction whereby the expense of providing more than one connection for 25 the accomplishment of these functions is obviated and whereby the hazard of freezing the dust collecting apparatus which is today felt is overcome.

A further object of my invention lies in the provision of a single casting so constructed that the air which is forced through the air pipe of the car is utilized for the purpose of discharging the dust, moisture, and all foreign particles with 30 which the air may be laden from the pipe line and at the same time to provide for draining the casting of any such accumulations of foreign particles.

The present practice of removing the dust 35 from air pipes consists in removing screw plugs from one or more points along the length of the pipe and this operation is only done when the car shall have been removed on a repair track and this requires 40 considerable time and expense to assure that the air pipes are in good order and working condition. It has been found that the moisture present in the air pipes even if collected in the present types of union and 45 similar pipe connections results in the freez-

ing and breaking of the entire connection and necessitates frequent inspection of the entire dust collecting apparatus.

The consequence of this invention is to cheapen the cost of installing a dust collecting device and cut-off valve in an air line system and to locate a single connection at a point where the same may be more readily accessible for the purpose of inspection and repairs than has hitherto been found to be 60 the case, as well as to efficiently provide for discharging the dust and draining the moisture that may be present in the air pipes of 65 said system.

With the above and other objects in view 70 my invention consists in the combination, arrangement, and details of construction disclosed in the specification and accompanying drawings, and then more particularly pointed out in the appended claims. 75

In the drawings, wherein similar reference characters designate similar parts throughout the respective views, Figure 1 is a side elevation of my invention showing it mounted in proper position upon an air 80 line of pipe. Fig. 2 is a sectional view of my invention, Fig. 3 is a detailed view of a deflector to be described, Fig. 4 is a sectional view of a cleaning valve and accessories to be described, Fig. 5 is a sectional 85 view of a modified form of my invention, and Fig. 6 is a sectional view of the deflector mechanism of my modified invention.

Referring to the drawings which are merely illustrative of my invention 1 denotes a suitable T-coupling or union which is provided at one end with an inlet pipe 2 and at the opposite end with an outlet pipe 3 substantially equal in diameter to the inlet pipe 2. A cut off valve of any desirable 90 construction embraces a plug 4 provided with an operating handle 5 and fitting in the usual plug seat 6 formed internally of the inlet pipe 2, the plug being provided with a port 7 with which is adapted to register the port 8 formed in the plug seat 6. The internal configuration of the union will be irregular so that metal will be massed at such points as will be effective to provide a passage 9 leading immediately from the 95 inlet pipe 2, an admission passage 10 of a diameter less than one-half the diameter of the inlet or outlet port leading downwardly from the passage 9 and an upwardly extending discharging passage 11 a diameter 100

105

110

less than one-half of the diameter of said inlet or outlet port communicating with the outlet pipe 3. By this construction it will be seen that a circuitous course and passage 5 is provided for the air in passing from the inlet into the outlet pipes.

12 denotes a suitable deflector which in this instance is shown in the form of a concavo-convex hood the same being sustained 10 in position directly underneath the passage 10 by such means as upright stems 13, the latter being provided so as to provide clearance spaces for the passage of the collectings deposited by the air passing 15 through the said passages out of the outlet pipe 2.

A special mounting and connection is provided which is adapted to be removably secured to the pipe union 1 and which carries 20 or may carry the deflector 12. This mounting is virtually a valve casing 15 having a threaded nipple 14 threaded into the pipe union and this valve casing has a bore 16 extending from end to end thereof. Formed 25 in the casing 15 is a conical seat 17 adapted to receive the conical plug 18. It will be seen that the conical valve seat 17 communicates with an annular chamber 17'. The conical plug 18 is provided with a 30 spring socket 19 into which projects one end of a coiled spring 20 the opposite end being snugly received in the spring cap 21 which is threaded into the annular chamber 17', a nut 22 being integrally formed upon 35 said cap whereby the same may be readily removed. The spring 20, it will be understood, will be put under tension so as to cause the conical plug 18 to lie snugly in its seat. The plug 18 is provided with a 40 transverse opening 23 which, when the plug shall have been rotated a satisfactory distance, will register with the bore 16 formed in the valve casing 15. An operating handle 45 24 serves to rotate the valve plug to bring its port or opening 23 into registration with the bore 16 so as to provide a clear passage for the escape of dust and drainage.

24' denotes a nipple formed upon any 50 part of the air pipe line and the outlet pipe 3 of applicant's union 1 will be threaded upon said nipple thereby establishing inter-communication between the union and said air line at one point and by means of suitable pipe connections engaging the inlet end 55 of the union 1 which latter will be properly mounted in position. It is contemplated that the union 1 should be so located as to make it easy for the same to be inspected 60 and cleaned if desired.

Rust scale and dirt collects in the dust 65 collector which applicant provides and which is formed at the lower end of the union in the space surrounding the stems of the deflector, and through the use of the plug or valve 18 it will be possible for any

train man or inspector to clean out this union while testing air on trains. The important feature of draining the air line cannot be overlooked as water accumulates from moisture in the air pumped into the 70 train line and then collects in the bottom of the dust collector and would ordinarily freeze causing the pipes to burst thereby causing a great amount of delay to the cars in transit. By means of applicant's valve 75 18 the bottom of the dust collector can be opened at any time so that no dust can accumulate which cannot be readily expelled. By opening this valve the car charged with air will serve the useful purpose of enabling 80 this air to expel the foreign particles. The air entering through the inlet pipe, 2 will pass downwardly through the admission passage 10 when its path will be broken thereby affording an opportunity for any 85 dust or moisture to settle upon the deflector whence the same will be diverted into the dust collector and will remain there as long as the port or opening 23 formed in the conical plug 18 is out of registration with the bore 16 formed in the valve casing 15. The air being thus rid of its foreign particles 90 and having its course diverted will pass upwardly through the passage 11 out of the outlet pipe 3 to continue its flow to the point 95 where desired. Of course the handle 5 controlling the operation of plug 4 may be manipulated to cut off the supply of air as may be desired. When the opening 23 is in registration with the bore 16 and air is passing 100 through the union 1 the same will expel the dust or moisture through the bore 16 so as to thoroughly clean and drain this section.

I show a modified form of my invention which consists of the same type of union hitherto described except as concerns the construction of the drain valve which will now be set forth. The deflector 25 is of the same shape as the deflector 12 already described and it is supported upon a stem 26 which is connected to a plug 27 arranged to close a plug seat 28 formed upon a tube 29 removably connected to the union and 30 is a spider supported in said tube 29 through which passes the rod or stem 26. A spring 31 is coiled around the rod 26 and bears at one end against the spider and rests at its opposite end upon the oppositely disposed levers 32 which are suitably fulcrumed upon pivots 33 provided in the clearing spaces in the tube 29, said levers being disposed obliquely with respect to said stem and being operated by means of such flexible elements as cords 34. The cords 34 will lead to any desirable point along the air line and when said cords are pulled the levers will be forced upwardly thereby putting the spring 31 under tension unseating the plug 27 which is free to move with the stem 26

thereby enabling the air under pressure to expel the dirt or moisture from the union out of the bore 35 formed in the tube 29. It will thus be seen that this modified form 5 of my invention is adaptable to those conditions where it is desired to actuate the valve controlling the discharge of the dust from some distant point.

Numerous modifications may be resorted 10 to in practice without departing in principle from the details of construction herein disclosed.

What I desire to claim and secure by Letters Patent is:—

- 15 1. A dust and water trap for fluid pressure lines, comprising a T-shaped coupling having formed therein an air inlet port, an air outlet port, and a circuitous passage of a diameter less than one-half of said inlet 20 and outlet ports connecting said inlet and outlet ports and having its intermediate portions enlarged to form an expansion chamber, a concavo-convex deflector in said chamber, and means journaled in the walls 25 of said coupling for establishing communication between said expansion chamber and the atmosphere.
2. A dust and water trap for fluid pressure lines comprising a T-shaped coupling

having formed therein an air inlet port, an 30 air outlet port, an expansion chamber, an air admission passage establishing communication between said air inlet port and said chamber, and a discharge passage establishing communication between said outlet port 35 and said chamber, a deflector having a convex upper surface in said chamber, the access of said admission and discharge passages intersecting at the upper surface of said deflector, and means journaled in the 40 walls of said coupling for establishing communication between said expansion chamber and the atmosphere, said means comprising a plug rigidly connected to said deflector, a casing threaded into said coupling, said casing having a valve seat to receive said plug, a coil spring for seating said plug and levers swingingly mounted on said casing and pivotally connected to said plug whereby the latter can be unseated against the 50 tension of said spring.

In testimony whereof I affix my signature in presence of two witnesses.

JOSEPH N. SUPRUNOWSKI.
